(57) **CLAIM**

I claim the ornamental design for a burp pad, as shown and described.

DESCRIPTION

FIG. 1 is a perspective view of a burp pad showing my new design;

FIG. 2 is a perspective view of the present invention folded in half with reverse side visible;

FIG. 3 is a front elevational view thereof;

FIG. 4 is a rear elevational view thereof;

FIG. 5 is a left side elevational view thereof;

FIG. 6 is a right side elevational view thereof;

FIG. 7 is top plan view thereof;

FIG. 8 is bottom plan view thereof; and,

FIG. 9 is a perspective view thereof, showing the invention in the position of use.
The broken lines showing a human figure and infant in FIG. 9 illustrate the portions of the design that form no part of the claim.
